UNITED STATES PATENT OFFICE.

ELIJAH SHAW, OF MILWAUKEE, WIS., ASSIGNOR OF ONE-HALF TO CHARLES T. BRADLEY AND WILLIAM H. METCALF, BOTH OF SAME PLACE.

HEEL-STIFFENER MACHINE.

SPECIFICATION forming part of Letters Patent No. 356,335, dated January 18, 1887.

Application filed April 3, 1886. Serial No. 197,658. (No model.)

To all whom it may concern:

Be it known that I, ELIJAH SHAW, of Milwaukee, in the county of Milwaukee and State of Wisconsin, have invented new and useful Improvements in Machines for Forming Heel-Stiffeners; and I do hereby declare the following to be a full, clear, and exact description of said invention, reference being had to the accompanying drawings, and to the letters or figures of reference marked thereon, which form a part of this specification.

The object of my invention is to provide a machine that will automatically shape and mold a heel-stiffener, which machine operates rapidly, requires but little attention, and is not liable to get out of repair or to quickly wear out.

The peculiar construction of the parts of the machine and its operation will be understood from the following description, with a reference to the accompanying drawings, in which—

Figure 1 is a perspective of the complete machine. Fig. 2 is a vertical central section longitudinally of the machine. Fig. 3 is a plan of a portion of the forming mechanism. Fig. 4 is an under side view of a part of the mechanism for operating the forming mechanism. Fig. 5 is a vertical cross-section of the machine on line X X of Fig. 2, showing also parts to the right of the line of cross-section. Figs. 6, 7, 8, and 10 are details. Fig. 9 is a vertical cross-section of the presser-head.

The same letters refer to like parts in all the views, and arrows indicate the direction of the motion of the wheels.

The operative mechanism is all supported on a rigid frame, A. A former, I, is affixed rigidly to the top of the frame, near one end centrally, and projects inwardly on the top of the frame. This former is vertically about the same thickness as the height of the to-be-made heel-stiffener, and its horizontal shape at the front or inner end is about that of the heel of a small-sized human foot, gradually narrowing somewhat horizontally in the rear of the front wider part, thus making it still further to correspond with the form of the human foot. The former is corrugated vertically, whereby it grasps and holds the stiffener firmly while being shaped.

On the top of the frame, in front of the former I, are two molding or shaping jaws, 2, which are pivoted at their rear ends on a slide, 3, so as to have a horizontal movement of their front ends. The front ends of these jaws 2 are held together against each other yieldingly by inwardly-pressing springs 4, affixed to the rear end of the jaws and bearing against a pin in the slide. The front ends of the jaws 2 are cut out or recessed, forming a mold or shape, 5, adapted to receive and fit closely to the former I. This mold or shape is cut equally from each of the two jaws 2, and is preferably lined with a sheet-metal spring-lining, 6, affixed at its outer ends to the outer front ends of the jaws, and fits snugly to the inside of the mold when the jaws are held together, and has sufficient elasticity to permit the jaws to separate slightly, so that the narrower front end of the shape 5 may pass the wider front end of the former I when the jaws are pressed up to and against the former I, as will be hereinafter described.

The slide 3, carrying the jaws 2, has a reciprocating movement forward and back on the frame, and is operated as follows: The driving-shaft 7, on which is the power-receiving band-wheel 8, is provided with a pinion, 9, meshing with the gear-wheel 10, supported on and rotating with an arbor having bearings 80 in the frame. A pitman, 11, connects the gear-wheel 10 with the sector-gear 14. The pitman 11 has a slot, 12, Fig. 8, in which a sliding block receiving wrist-pin 13, eccentric on gear-wheel 10, fits and slides, carrying the pitman; but by the slot 12 a certain amount of lost motion between the gear-wheel 10 and sector-gear 14 is provided for. The sector-gear 14, oscillating on a shaft, 15, supported in the frame, meshes with pinion 16, supported and rotating on an axle, 17, having its bearings in lugs 18, 18, projecting inwardly, one on each side of the pinion, from the under side of the slide 3. The pinion 16 meshes with straight rack 19, which rack is supported on the frame A and is adapted to be alternately connected rigidly to and movable in this frame. This rack 19 is supported in dovetailed ways 20 on each side rigid to the under side of the top of the frame, and in these ways 100

the rack has a reciprocating endwise movement. Rigid on its front end this rack 19 has a head-piece, 21, to which the connecting-rods 22 22, one on each side, are pivoted, which 5 rods, at their rear ends, are pivoted in one end, respectively, to the short lever-arms 23 23, which arms, at their other ends, are each rigid to a pivoted bolt, 24, which bolts pass up through and turn in the top of the frame, 10 and carry rigidly on their respective upper ends the lever-arms 25 25, the free ends of which extend inwardly and are adapted to bear against the outer sides of the jaws 2 2, near their front ends, and close these jaws 15 tightly against the former 1.

To obviate binding, the arms 25 25 are provided with anti-friction wheels 26 26 in their free inner ends, which impinge against the jaws 2 2. A pin, 27, having endwise movement, passes through one of the flanges forming the rigid way 20, and enters an aperture therefor in the rack 19. The pin at its outer end is supported in a lug, 28, rigid on the frame. About this pin 27, and rigid thereto, 20 just outside of the way 20, is a collar, 29, and around the pin, between collar 29 and lug 28, is a coiled spring, 30, bearing against the collar and lug at its respective ends, whereby the pin is pushed forward, so that its inner end 25 enters the rack, as provided for, and holds the rack in position. An arm, 31, affixed at its rear end to the under side of the slide 3, extends forwardly, and is provided at its front end with beveled fingers adapted to impinge 30 against the inside of collar 29 and force the pin 27 out of the rack 19.

It will be seen that as the wheel 10 rotates (from the position shown in Fig. 2) it will force the sector-gear 14 forward, and will 40 thereby carry slide 3 forward, so that the jaws 2 2 will inclose the former 1 in the recess 5, and just at the moment that the jaws come to this position the arm 31 will withdraw the pin 27 from the rack 19, and the rack being then 45 free to move endwise will, by the slightly-continued motion of the sector-gear 14, be moved to the rear, throwing the arms 25 25 around against the ends of the jaws 2 2 and pressing them firmly against the former 1, and by the continued rotation of wheel 10, after the lost motion provided for by slot 12 in pitman 11 has 50 been had, the rack 19 will, by the reverse motion of the sector-gear, be first carried forward until the head 21, Fig. 2, strikes the frame, 55 when the slide 3 will be forced back, the pin 27 re-entering the rack as soon as the fingers on arm 31 are withdrawn from beneath the collar 29.

To form the inwardly-extending flange at 60 the bottom of the heel-stiffener, a reciprocating presser is provided. This presser is constructed of a bar or beam, 32, extending horizontally across the machine above the jaws 2 2 and former 1, and at each of its ends it has 65 an arm, 33, affixed centrally and rigidly thereto, which arm 33 is pivoted at each end to downwardly-extending supporting-rods 34 34, which

rods, at their lower ends, are pivoted to a horizontal arm, 35, which arm 35 is centrally supported on a shaft or arbor supported on the frame A. By thus supporting the beam 32 it may be oscillated to the front and rear, and the bottom face of the beam remains constantly in a horizontal plane, or parallel with the top of frame A. 70

Just beneath the beam 32, centrally, is a presser-foot, 36, Fig. 10, which foot has an inwardly-curved front end, and is also provided with a laterally-extending horizontal roller, 37, in a recess therefor in the presser-foot. 80 This roller 37 has journals at each end, having their bearings in the walls of the presser-foot 36. Extending upwardly rigidly from the presser-foot is a stem, 38, which is provided with a rigid collar or shoulder, 39, about it at 85 and just above the presser-foot, which collar 39 enters and fits in the lower end of a chamber, 40, formed in and above the beam 32, in the top of the walls of which chamber a screw-threaded tension-nut, 41, is fitted and turns. 90 The stem 38 extends upwardly through and is guided by the tension-nut 41, and a spring, 42, coiled around stem 38, is inserted between the collar 39 and tension-nut 41. The roller 37 travels on and bears against the top of the jaws 2 2, and is held steadily down to its work by the spring 42. Two guide pins, 43 43, extending rigidly upward from the top of the presser-foot 36, enter apertures therefor in the beam 32 and keep the presser-foot in position 95 relative to the beam, permitting only a slight vertical movement as the beam 32 oscillates forward and back on the rods 34.

The presser-beam 32 is pivoted to one end of the connecting-rod 44, which rod, at its other extremity, is pivoted eccentrically to the rotating friction-disk 45, which friction-disk is provided with a rigid arbor, 46, Fig. 5, extending rearward and having bearings and rotating in the frame A. This disk and its arbor 46 have no lateral motion, they being confined to a rotary motion by a nut on the arbor on the outside of the frame and a collar rigid on the arbor just inside of the frame. A friction-wheel, 47, and a pinion, 48, affixed thereto, 105 are supported and rotate on the arbor 46. The rim of the wheel 47 projects outwardly over and about the periphery of the disk 45, the inside of the rim and the periphery of the disk being correspondingly beveled, so as to fit 110 against and clutch each other when brought into contact by mechanism hereinafter described. The friction-wheel 47 and pinion 48 have a slight lateral movement on the arbor 46, which is produced by and through an arm, 115 49, rigid at one end on the reciprocating rod 50, the forked end of which arm 49 rides in a groove, 51, about the hub of the pinion and wheel 48 47. The rod 50 is supported and has reciprocal motion endwise in bearings in the 120 frame A, and has a coiled spring, 52, about it inserted between the frame and a collar on the rod, which spring, by and through the arm 49, rigid on the rod, forces the wheel 47 and pin- 125

ion 48 back away from the disk 45. A lever, 53, pivoted at its lower end to the frame, is at its upper end attached to the rod 50. This lever 53 is provided centrally with a bearing-wheel, 54, which impinges against a segmental guard or way-strip, 55, affixed to the side of the wheel 10, whereby when the wheel 54 is in contact with the way-strip 55 the rod 50 is forced forward, overpowering spring 52, and 10 the wheel 47 is brought into contact with the disk 45. The pinion 48 meshes with the gear-wheel 56, rigid on the driving-shaft 7.

It will be seen that the friction-wheel 47 rotates constantly when the driving-shaft 7 is in motion, and that while the lever 53 is in contact with the way-strip 55 the wheel 47 will be held up against the disk 45, whereby a reciprocating motion will be imparted to the presser. A lug, 57, on disk 45, is adapted to impinge 20 against and lie upon the outer free end of a coiled-spring buffer, 58, contained in a case affixed to the reciprocating rod 50, which buffer is withdrawn from the line of motion of the lug 57 as the wheel 47 is thrown into contact 25 with the disk 45, and is returned to position in front of the lug as the wheel 47 and disk 45 are separated.

On the top of the frame, just in front of the former 1, is provided a pair of holders adapted 30 to receive and hold the leather of which the stiffener is to be formed. These holders are convenient for use with some kinds of leather, but are not necessary for the perfect working of the machine ordinarily. These holders consist each of an inwardly-projecting bifurcate finger, 59, adjustably attached at its rear end to the top of the frame, jointed centrally, and having the free inner bifurcate ends flattened vertically, so as to be adapted to receive and 40 hold upright the leather strip between the bifurcate ends. These fingers are a little distance apart, so that the strip of leather of which the stiffener is to be formed may be set within them, extending from one to the other 45 in front of the former 1, and as the jaws 22 are moved forward to and about the former the front ends of the jaws will strike against the leather and the inner ends of these fingers 59, and will swing them back on their joints, 50 as indicated by dotted lines in Fig. 3, and the leather by the forward movement of the jaws will be withdrawn from the fingers as it is forced around the former. A small spring, 60, in front of each of these fingers, forces it back 55 to position as the jaws are drawn back. The motion of this machine is such that when the wheel 10 comes to the position shown in Fig. 2 there is then lost motion in the pitman-moved mechanism until the wrist-pin therein 60 moves to the inner end of slot 12 in the pitman, and during this time, the presser being at the rear end of its travel and not over the former 1, the leather for a stiffener is inserted in the holders 59, and when the wheel 10 65 has made a half-revolution, carrying the wrist-pin forward to the opposite or front side, the jaws 22 have been forced forward about the

former 1, and the guide 55 enters under the lever 53, throwing the friction-wheel 47 into contact with the disk 45, whereby the presser 70 is given its reciprocating motion, of which there are eight strokes, while the lost motion between wheel 10 and the pitman occurs as the wrist-pin on the wheel passes from one end to the other of the slot in the pitman. 75

It will be understood that the strip of leather of which the stiffener is formed is wider than the height of the former 1, and that after it is placed in the holders 59 it is first bent around the former by the jaws 22, and the part projecting above the former is, when the presser is set in motion, turned inwardly by the curved front end of the presser-foot 36, and, as the presser-foot passes and repasses over it, is pressed down, forming the inwardly-projecting flange of the stiffener. 80

What I claim as new, and desire to secure by Letters Patent, is—

1. In a machine for manufacturing heel-stiffeners, a stationary former, in combination 90 with two swinging shaping-jaws closed yieldingly by springs and pivoted on a movable slide provided with mechanism whereby the jaws are moved up to and withdrawn from the former, and a reciprocating presser operated independently of the slide-moving mechanism, all arranged and operating substantially as described.

2. In a heel-stiffener machine, the stationary former 1, in combination with the movable jaws 22 and the adjustable jointed holders 59, substantially as described. 100

3. In a heel-stiffener machine, the movable jaw-supporting slide 3, in combination with and operated by a rack, pinion, sector-gear, 105 and pitman provided with a slot and attached to the wrist-pin of a wheel, whereby a reciprocal movement with a certain amount of lost motion is secured, substantially as described.

4. In a heel-stiffener machine, the rack 19, 110 constructed to travel in ways in the frame and operated by suitable mechanism, in combination with the swinging arms 25, connected to the rack by pivoted rods, and the movable jaws 22, substantially as described.

5. In a heel-stiffener machine, the rack 19, 115 constructed to travel in ways on the frame, with the thereto-connected and thereby-operated arms 25 and the spring-actuated bolt 27, in combination with the movable slide 3, provided with arm 31, and the pinion 16, supported and rotating in lugs rigid on the slide 3, which pinion meshes with and is operated by an oscillating sector-gear, substantially as described. 120

6. In a heel-stiffener machine, the presser-arm 32, provided with a chamber, 40, for the reception of the stem of the presser-foot, in combination with the presser-foot 36 and the therein-rotating roller 37, substantially as described. 130

7. In a heel-stiffener machine, the presser-arm 32, supported on rods 34 34, to which it is pivoted in their upper ends, which rods are

pivoted and supported at their lower ends on the frame, substantially as described.

8. In a heel-stiffener machine, the arm 32, supported and oscillating on rods 34, 34, in combination with the presser-foot 36, having stem 38, and the spring 42, substantially as described.

9. In a heel-stiffener machine, the gear-wheel 56, rigid on the driving-shaft, the friction-wheel 47, rigid to pinion 48, meshing with gear-wheel 56, and friction-disk 45, provided with a rigid arbor, 46, which supports pinion 48 and wheel 47, in combination with reciprocating rod 50, which carries the rigid finger 49, which rod is actuated by a spiral spring, 52, and a cam-actuated lever, 53, substantially as and for the purpose described.

10. In a heel-stiffener machine, the gear-wheel 10, provided with a segmental guide or way-strip, 55, in combination with the lever 53, provided with a bearing, 54, in combination with the reciprocating rod 50 and the actuating-spring 52, substantially as described.

11. In a heel-stiffener machine, the lug 57, rigid on the disk 45, in combination with the buffer 58, attached to the reciprocating rod 50, substantially as described.

12. In a heel-stiffener machine, a presser attached by a connecting-rod, 44, eccentrically to a friction-disk, 45, in combination with lever 53, bearing intermittently against a guide, 55, on wheel 10, the thereby-actuated reciprocating rod 50, provided with spring 52 and finger 49, and the friction-wheel 47, guided by finger 49, and geared to the driving-shaft of the machine, whereby a reciprocating motion is obtained intermittently by the presser, substantially as described.

13. In a heel-stiffener machine, a reciprocating presser-foot, 36, provided with an inwardly-curved front end, and a horizontally-rotating roller, 37, substantially as described.

14. In a heel-stiffener machine, the presser-arm 32, having a chamber, 40, in combination with the presser-foot 36, provided with a stem 45 adapted to enter chamber 40, and a spring, 42, adjusted by nut 41, substantially as described.

In testimony whereof I affix my signature in presence of two witnesses.

ELIJAH SHAW.
